UNITED STATES PATENT OFFICE.

HARRY FRANKLIN FRANTZ, OF CLEVELAND, OHIO.

CRUTCH ATTACHMENT.

Application filed December 8, 1927. Serial No. 238,669.

My invention relates to that class of devices which are designed to provide means to keep the crutch from slipping when walking on ice or other slippery places, which means 5 may be retracted and brought out of engagement with the ground or other surface walked upon.

Devices of this kind with which I am familiar are too costly and complicated. My 10 invention has for its object to provide a novel attachment which is simple and cheap.

My means of accomplishing the foregoing may be more readily understood by having reference to the accompanying drawings 15 which are hereunto attached and are a part of this specification, in which similar characters of reference indicate corresponding parts in all the figures.

Figure (1) is a side elevation of my invention attached to the end of a crutch.

Figure (2) is a vertical cross section of the sleeve and common rubber tip as they appear when attached to the end of a crutch.

Figure (3) is a side elevation of my ferrule.

Figure (4) is a side elevation of my sleeve.

Figure (5) is a plan view of the ferrule as seen in Figure (3).

Figure (6) is a plan view of the sleeve as seen in Figure (4).

30 "A" represents the crutch. "B" the extreme end of crutch that carries the rubber tip (4), commonly used on all crutches.

The invention consists of a sleeve (1) and is equipped with a plurality of vertical bars 35 (2), and cog-like teeth (3), on the bars (2) and a ferrule (7). This ferrule is equipped with a plurality of vertical pockets (8) and each pocket provided with a cog-like tooth (11). These teeth are at the top of pockets (8) and the width of these teeth (11) employ half the width of pocket (8) as shown in Figure (5).

To install and operate my invention first fit the sleeve (1) to the crutch "A", to bear against the shoulders (5), then place the two 45 screws or small brads through the holes (6). The rubber tip (4) will then be on the extreme end of "B", making it unnecessary to shorten the crutch to install my invention.

The ferrule (7) can then slide over and up by pockets (8) provided, to member with the bars (2); raise until the center of sleeve (1) is reached, then one quarter inch turn to the right and the cog-like teeth (11) will cooperate with cog-like teeth (3), then drop the 50 key (9) into top of pocket (8) and the ferrule is locked and is ready to walk on slippery 55 places by using inside bevel edge (10). As the bottom of ferrule becomes worn down from use and sharpening you can drop down 60 to a lower position.

When wishing to use the rubber tip (4), pull out the key (9), turn one quarter inch to left and raise the ferrule (7) to top of sleeve (1), turn one quarter inch to right and drop 65 in the key (9) and this will bring the rubber tip (4) into use.

Having thus described my invention, I claim as new and desire to secure Letters 70 Patent:

In a crutch a sleeve adapted to be fixed to the foot of the crutch, said sleeve being provided with a plurality of vertical tenons carrying cog-like teeth, a ferrule provided with a plurality of radial pockets 75 adapted to accommodate the tenons of the sleeve, said pockets each provided at its opening with a tooth, to cooperate, upon turning the ferrule and sleeve relatively with any desired one of the cog-like teeth carried by 80 the tenons.

HARRY FRANKLIN FRANTZ.
